UNITED STATES PATENT OFFICE.

BAINBRIDGE W. BURDICK, OF ALBANY, NEW YORK.

DESIGN FOR A STOVE-DOOR-CATCH SHELL.

SPECIFICATION forming part of Design No. 28,764, dated May 31, 1898.

Application filed March 4, 1898. Serial No. 672,611. Term of patent 14 years.

To all whom it may concern:

Be it known that I, BAINBRIDGE W. BURDICK, a citizen of the United States, residing at Albany, in the county of Albany and State 5 of New York, have invented and produced a new and original Design for Stove-Door-Catch Shells, of which the following is a specification, reference being had to the accompanying drawings, forming part thereof.

10 Figure 1 is a perspective view of a door-catch shell, showing my new design viewed from its front end. Fig. 2 is a perspective view of the same viewed from its rear end. Fig. 3 is a view of the same from above.

15 As shown in the drawings, the leading or material feature of my design consists of a shell having the shape or configuration shown when viewed in perspective and from above, as shown in the several figures. In this shape 20 or configuration of the shell A the inclined upper edge *a* gradually tapers in its width as

it runs forward from the rear end notch *b* to the front end of the shell, and the lower edge *c* is convex in form in direction of its length, with its curve gradually growing sharper as 25 it approaches the front terminal of the inclined upper edge *a*, as shown in Fig. 1. The lateral sides *d d* are inclined toward each other as they extend forward in direction of the length of the shell, as shown in Fig. 3. 30 At the rear end of the inclined upper edge *a* is notch *f*, which is angular in form and terminates at the rear ends of the lateral sides *dd*.

Having described my invention, what I claim as new, and desire to secure by Letters 35 Patent, is—

The design for a stove-door-catch shell as herein shown and described.

BAINBRIDGE W. BURDICK.
